MACHINE FOR DISTORTION CORRECTION
IN METAL PLATE

George Lee Miller, Canton, Ohio

Application January 31, 1941, Serial No. 376,914

4 Claims. (Cl. 153—52)

This invention relates to the straightening or the bringing to correct contour of distorted metal plates, particularly such metal plates as are used for armor plate.

In the working, heat treatment and forming of metal plates, it has been extremely difficult to produce a plate conforming to the exact contour desired, for due to the internal stresses set up during treatment warpage of the plate will occur when cooling. Such warped plates have in the past been straightened or brought to contour by presses with the plate manipulated manually but such practice can only be used for small and relatively thin plates. The trend in the past few years has been toward the use of heavier and heavier metal plates for armoring of tanks, trucks, airplanes and other equipment of either the mobile or stationary type and it has been found extremely hard to produce plates to the proper contour by use of existing methods, for it is practically impossible to so shift and control the heavy plates as to obtain the proper straightening action by the press while maintaining any reasonable rate of production. Furthermore, the shifting of the extremely heavy plate requires a large number of men and during times of national emergency it is necessary that as many men be released as possible from shop work. It is an object, therefore, of the present invention to provide a means for straightening or contouring of metallic plates more accurately and with a minimum of manual labor.

A further object of the invention is the provision of a means for straightening or contouring metallic plate with a minimum of movement of the plate itself.

A still further object of the invention is the provision of an improved means for straightening or contouring metallic plate by applying pressure thereto at predetermined points and in predetermined repeatable sequence.

A yet further object of the invention is the provision of a straightening or contouring means for metallic plates, which straightening or contouring means may be so operated as to insure a substantially uniform distribution of stresses placed in the plate during straightening or contouring thereof.

These and other objects of the invention will be apparent to persons skilled in the art from a study of the following description and accompanying drawings, in which:

Figure 1 is a partial front view of an improved machine for straightening or contouring metal plate;

Fig. 2 is an end view of the machine shown in Figure 1;

Fig. 3 is a sectional view taken substantially on line 3—3 of Fig. 1;

Fig. 4 is an enlarged view of the movable die with a portion broken away to better disclose the means for causing horizontal movement of the die;

Fig. 5 is a sectional view taken substantially on line 5—5 of Fig. 6 and showing the drive shaft and connection for causing horizontal movement of the die;

Fig. 6 is a sectional view taken substantially on line 6—6 of Fig. 5;

Fig. 7 is a front view similar to Figure 1 but showing a slight modification of the means for causing longitudinal shifting of the die, and

Fig. 8 is an end view of the machine shown in Fig. 7.

Referring now to the drawings in detail, it will be seen that the machines shown in Figs. 1 and 7 are of generally the same form comprising side pieces 2 formed intermediate their height with a throat opening 4 and joined together by an upper tie plate 6 as well as by a base plate 8, thereby forming an extremely rigid frame with the space between the uprights wide open so that work of any length may be fed through the machine and of a width substantially equal to the width between uprights. The uprights are additionally tied together below the throat openings by means of the front plate 10 carrying at its upper end an enlargement 12 forming a table or platform upon which the stationary die 16 may be fastened in any suitable manner. This die, of course, may be of any suitable form but in the present case is provided with spaced removable portions 18 formed of extremely hard metal to resist the thrust placed thereon.

The movable die A, which is shown as adapted to be reciprocated vertically relative to the stationary die, is clamped to a die slide 20 by means of die slide clamp 22, all as clearly shown in Figs. 2 and 3. The die slide is formed with a projection 24 (Figs. 3 and 6) adapted to fit in a recess in the ram 26 and be firmly clamped thereto by a ram clamp 28 which will not only hold the die slide to the ram but will transfer loads from the slide to the ram proper. The ram is moved vertically by means of thrust rods 30 having ball and socket connection at the lower ends with the ram and at the upper ends being mounted upon an eccentric formed on shafts 32. These shafts are driven by means of gearing 34 which is in turn driven by a motor or any other suitable source

of power, preferably clutched to the gearing and with the clutch controlled by means of foot treadle 36. It is, of course, obvious that this foot treadle may directly and mechanically control the clutch or it may control the flow of current to a magnetic clutch, or to an electric operator of the mechanical clutch in any well known manner. The thrust rods 30 are provided with micrometer adjustments in order that the lowermost position of the ram and accordingly the die face may be accurately controlled. The adjustments of the thrust rods may be independent of each other in order to permit slight tilting of the ram, or they may be interlocked so as to be movable in unison. Insofar as the machines of Figs. 1 and 7 are concerned the preceding description applies to both and accordingly the same reference numerals have been used.

In Figs. 1, to 6 inclusive the machine has been modified by attaching thereto a means for causing longitudinal movement of the die relative to the ram. In this case the die A has attached thereto at its rear face a block 40 secured in position by bolts or other means 42. This block is internally threaded to receive lead screw 44 journaled at its ends in bearings 46. These bearings, as clearly shown in Figs. 5 and 6, are formed with a bearing portion shaped to receive the ball bearings or other antifriction means 48 and also formed with projections 50 and 52, the former being clamped in position by the die slide clamp, while the latter is fastened by means of bolts 53 directly to the die slide. The antifriction means is held in place and protected by means of an outer cap 54 which may be removed, thus permitting removal of the entire lead screw and antifriction bearing assembly without necessitating removal of the bearing supports from the die slide. It will, of course, be obvious that if desired the entire assembly may be removed from the ram by removal of the die slide. The lead screw projects through one of the bearings as clearly shown in Figs. 1 and 5 and has keyed thereto pulleys 56 adapted to receive belts 58 which connect them to the pulleys 60 carried on the armature shaft of a reversible motor or other prime mover 62 fastened on and movable with the ram. In the instance shown the prime mover for the lead screw is a reversible torque motor with its current supply controlled in conjunction with the ram movement so that the die cannot be moving when it is lowered upon the work to apply deforming pressure. However, by provision of the torque motor no damage to the parts or overheating of the motor will be occasioned even if the die should be moving horizontally when it comes in contact with the work. In order to properly lubricate and permit easy movement of the die in the die slide as well as of the lead screw in the die block, lubrication openings 64 and 65 respectively (Fig. 3) have been provided.

In the slight modification shown in Figs. 7 and 8 the lead screw 70 is provided with both right and left hand threads and is supported for rotation on the ram by bearings 71 and 72. The lead screw shaft is extended beyond bearing 72 and carries at its outer end a clutching arrangement 74 by means of which it may be clutched or declutched with a gear 76 operated by a rack 78. The clutching device 74 includes an over-running clutch of the reversible pawl type in order that the lead screw may be driven only on either the up stroke or down stroke of the ram. This rack is provided with elongated slots 80 by means of which it may be attached to the ram ends for movement rela-

tive thereto and is guided by means of guide plate 82 fastened to the standard or upright of the machine. The rack is connected by pitman 86 to a ring 88 driven by the shaft 32. The position of the ring 88 on the shaft may be changed, thus varying the stroke and movement of the rack which, of course, will also control the amount of movement imparted to the lead screw and hence the die.

In each case whether the machine of Fig. 1 or Fig. 7 is being used the work W will rest upon the stationary dies and be fed directly into or out of the machine although it will, of course, be obvious that under certain conditions it may be desirable to have the work rest upon movable dies. In cases where bimetallic plates are being used the tendency is for the plate after heat treatment to assume a spherically curved shape with the hard portion on the upper or convex side and the softer portion on the concave or lower side. The relative ratio of hard to soft portions of the work has been indicated in Figs. 1, 2, 7 and 8 by the dotted line, with the thin portion indicating the hard part of the plate and the thicker portion the softer part of the plate. It is, of course, obvious that the bimetallic plate has been used merely for illustrative purposes for any metal plate could constitute the work. With the work placed on the stationary dies pressure on the foot treadle will cause the ram to operate and it will be driven vertically upward and downward away from and toward the work with its lowermost stroke position so adjusted as to force the curved plate a very slight amount beyond its true or final position in order that when the deforming pressure is relieved on the upward stroke of the ram the plate will remain in its proper and correct position. On the upward stroke of the ram the driving means for the lead screw, whether it be the motor or the rack and gear, will cause the movable die to slide horizontally relative to the ram in order that it will be in position to act upon a new area of the work on the next downward stroke of the ram. The terms vertically and horizontally as used here are merely descriptive of the movements of the machines shown and are intended to be synonymous with movements toward and across the work respectively and irrespective of the portion of the work in space.

It is obvious from the preceding description that the die may slide longitudinally of the ram, that is, across the surface of the work, at all times when the die is free of contact with the work but moving toward or away from the work, and it is also obvious that in the form shown in Fig. 1 the die may also slide relative to the ram at all times when the die is not in deforming pressure contact with the work irrespective of whether the ram is moving or not. With the die reciprocable with the ram in a vertical direction and slidable along the face of the ram it will be seen that the stresses on the ram will be distributed and not concentrated at one point and that the die has been given two degrees of freedom of movement. Also with the die slidable along the ram it is not necessary for the work to be moved in order that one strip of the work may be straightened or brought to correct contour. It is, of course, obvious that if one area in the strip to be operated on requires more than one stroke of the press or a greater or less overlap of the points of contact between the die and the work, such operation may be obtained without moving the work since the position of the die across the

work may be positively controlled. Furthermore, by reversal of the lead screw rotation a reversal and duplication of operations on the metal plate or work may be obtained without moving the metal plate or work. After straightening or bringing one strip of the work to proper contour the work will, of course, have to be moved into or out of the machine slightly to bring a new strip or area into position for contact by the dies. In most instances where the operations involve a mere straightening or bringing of a spherically curved plate to a plane surface the application of deforming pressure in definite positions and strips to an area wholly spaced within the borders of the plate will be sufficient to straighten the same, whereas in previous operations where full movement of the plate relative to stationary dies was necessary and definite position of impact could not be controlled application of pressure to substantially the entire plate area was necessary to straighten the same.

While the invention has been described more or less in detail by reference to drawings showing two forms, it is obvious that the invention is not limited to a specific type of machine but may be applied to any machine and involves broadly the movement of reciprocating dies relative to the main reciprocating parts in order that trips or areas of the work may be operated on without shifting the work in the machine. It is also obvious that various modifications and rearrangements of parts may be made by those skilled in the art and all such modifications and rearrangements of parts are contemplated as will fall within the scope of the appended claims defining my invention.

What is claimed is:

1. In a machine for bringing armor or other metallic plate to final contour the combination of a stationary die for supporting the plate, a vertically reciprocable ram, power-driven means to reciprocate said ram for application of deforming pressure to said plate, a movable die attached to said ram for sliding movement along the entire face of the ram, a twin-threaded lead screw carried by said ram and engaging said movable die to cause sliding movement thereof, and connecting means joining said twin-threaded lead screw and power-driven means and operable

by said power-driven means during upward movement of the ram thereby causing rotation of said lead screw.

2. In a machine for bringing armor or other metallic plate to final contour the combination of a stationary die for supporting the plate, a reciprocable ram, a movable die attached to said reciprocable ram for sliding movement along the ram, means carried by said reciprocable ram and connected to said movable die to cause sliding movement thereof, and additional means connected to said first named means to cause said sliding movement of the movable die along substantially the entire edge of the ram, said additional means including means operating to cause said sliding movement of the movable die only when said movable die is out of contact with said plate.

3. In a machine for bringing armor or other metallic plate to final contour the combination of a stationary die for supporting the plate, a vertically reciprocable ram, power driven means to reciprocate said ram for application of deforming pressure to said plate, a movable die attached to said ram for sliding movement along the ram, means connected to said movable die to cause sliding movement thereof, and connecting means joining said last named means and power driven means and operated by said power driven means during upward movement of the ram to cause a predetermined sliding movement of the movable die.

4. In a machine for bringing armor or other metallic plate to final contour the combination of a stationary die for supporting the plate, a vertically reciprocable ram, power driven means to reciprocate said ram for application of deforming pressure to said plate, a movable die attached to said ram for sliding movement along the ram, means connected to said movable die to cause sliding movement thereof, and connecting means joining said last named means and power driven means and operated by said power driven means during upward movement of the ram to cause said sliding movement of the movable die, said connecting means including a rack and gear and overrunning clutch device.

GEORGE LEE MILLER.
